WILLIAM N. BALLARD, OF KANSAS CITY, KANSAS.

COMBINATION WET AND DRY PIPE VALVE.

1,208,452.

Specification of Letters Patent. Patented Dec. 12, 1916.

Application filed May 6, 1916. Serial No. 95,824

To all whom it may concern:

Be it known that I, WILLIAM N. BALLARD, a citizen of the United States, residing at Kansas City, in the county of Wyandotte 5 and State of Kansas, have invented certain new and useful Improvements in Combination Wet and Dry Pipe Valves, of which the following is a specification.

My invention relates to a combination wet 10 and dry pipe valve, and one object is to provide a valve for sprinkler systems which will satisfactorily perform the functions of both a dry pipe valve and a wet pipe valve.

The valve is adapted to be placed at the 15 base of an automatic sprinkler system installed throughout a building to protect the same from fire, and said valve is adapted to be held in normal or closed position by either air or water pressure, as will herein- 20 after appear. The valve is so arranged that it will become automatically converted from a dry pipe valve to a wet pipe alarm valve in case the air pressure thereon weakens to the valve tripping point, or when the water 25 pressure on one side of the valve tends to open the same against the weakening air pressure on its opposite side.

Another object of my invention is to provide 30 a novel valve mechanism which when relieved of air pressure will open without shock or liability of damage to the mechanism.

Another object of my invention is to provide 35 a pipe valve mechanism which is simple in construction, not liable to get out of order, which is efficient in operation, which may be cheaply manufactured and easily and economically installed, and in which easy access 40 may be had to the internal mechanism thereof.

Other objects of the invention will hereinafter appear, and in order that said invention 45 may be fully understood, reference will now be made to the accompanying drawings, in which:

Figure 1 is a vertical sectional view of the 50 valve casing and seats, with the valves in closed position in solid lines and open in dotted lines. Fig. 2 is a detail of an arm and a valve to which it is connected. Fig. 55 3 is a cross section, reduced, on line III—III of Fig. 1. Fig. 4 is a modified form of valve.

Referring now in detail to the different 60 parts, 1 designates the valve casing which is, preferably, of the angular form disclosed by Fig. 1, and of substantially uniform diam-

eter throughout. The lower end of the casing 1 is adapted to be connected to a supply pipe (not shown) containing water under 60 pressure, and the upper end of said casing is adapted to be connected to the main pipe forming part of the usual automatic sprinkler system (not shown). The valve casing 1 is divided into a lower chamber 2, an intermediate chamber 3, and an upper chamber 4 by means of a vertically arranged valve seat 5 and a horizontal valve seat 6.

The valve seats 5 and 6 are, preferably, annular and the valve seat 6 is threaded into 70 the casing 1. The valve seat 5 is slidably mounted in a transverse annular flange 7 on the interior of the casing. Two stop rings 8 and 9 are mounted on the valve seat 5 at opposite sides of the flange 7 to limit the 75 sliding movement of said valve seat. The exterior of the valve seat 5 is embraced by a snugly fitting ring gasket 10 of compressible material such, for instance, as lead, adapted to be forced by water in the chamber 2 tightly against the periphery of said valve seat 5 and one side of the flange 7 and thus seal the joint between these parts. One side of the flange 7 is beveled to form an 80 annular wedge shaped groove between it 85 and the periphery of the seat. It is obvious that when the gasket 10 is forced by the water pressure toward the apex of the groove said gasket will snugly embrace both the periphery of the valve seat 5 and the 90 beveled side of the flange and thus effectually seal the intervening joint.

11 designates a vertically arranged valve mounted at its lower side upon a pin 12 and adapted to close the valve seat 5 and prevent 95 the passage of water from the chamber 2 to the intermediate chamber 3. The valve 11 is held in closed position by another valve 13, through the intermediacy of a lever 14 and a rod 15, which latter is pivoted at one end 100 to said valve 13 and at its opposite end to the free terminal of the lever 14. The valve 13 normally closes the seat 6 and is mounted upon a pivot 16. The upper end of the lever 14 is pivoted to a lug 17 and connected intermediate its ends by a pivot 18 to a small valve 19, adapted to close communication between the intermediate chamber 3 and the usual alarm system of which a tube 20 constitutes a part. The lower end of the tube 110 20 terminates in a seat for the valve 19 and is adjusted into proper relation to said valve by two lock nuts 21 engaging opposite sides of the wall of the casing 1. Access is had

to the interior mechanism through an opening 22 in one side of the casing 1 normally closed by a hinged door 23 firmly held in closed position by screws 24. In case of leakage past the valve 11, the water so leaking into the intermediate chamber 3 will run out through a ball drip valve 25. To more quickly drain the chamber 3, a discharge pipe 26 leading therefrom is provided and 10 has a shut off valve 27.

28 designates a drain pipe leading from the chamber 4 and provided with a valve 29, and 30 designates a pipe through which air is forced into the chamber 4 to provide 15 the proper air pressure upon the valve 13 to hold the same on its seat 6. The passage of air through the pipe 30 is controlled by a valve 31.

In practice, when the valve is adjusted for 20 a dry pipe system the valves 11 and 13 are closed and air pressure is admitted to chamber 4 to hold valve 13 closed, which in turn holds the valve 11 against its seat through the intermediacy of the rod 15 and the lever 25 14. Water under pressure is then admitted to the chamber 2, and flowing against the valve 11 and its seat 5, forces the latter against the former and compresses the lead ring gasket 19 against the periphery of the 30 seat 5 and the beveled side of the flange 7, thereby reliably sealing the intervening joint. With the parts arranged as disclosed, approximately, half of the water pressure against the valve 11 is borne by its pivot 12, 35 while the other half is transferred to the upper valve 13 through the lever 14 and the obliquely-arranged rod 15. A part of the pressure exerted against the valve 13 is borne by the pivot 16, so that a relatively 40 small amount of air pressure exerted upon the valve 13 will overcome the large amount of pressure exerted by the water against the valve 11 and thus reliably hold the two valves to their seats. The required air pressure upon the valve 13 may be further reduced by proportioning the parts so that the rod 15 may be adjusted nearer to a parallel 45 position with said valve 13 (Fig. 2), as the nearer such relation is attained the more 50 the lifting pressure on the valve 13 is transferred therefrom to its pivot 16.

Should a sprinkler head open from any cause and thus reduce the pressure of the air upon the valve 13 sufficiently to allow the 55 water pressure against the valve 11 to open the same, the water will flow through the intermediate chamber 3 and pass upward into the system through the chamber 4. As the valve 11 opens, it, through the intermediacy 60 of the lever 14 and the rod 15, starts to open the valve 13, so that when the water impinges against the underside of said valve 13 it fully opens the latter to the dotted line position Fig. 1. In the meantime the 65 valve 11 swings clear of the lever 14 and

opens to the dotted line position and the water is free to flow unimpeded through the casing 1 to the sprinkler heads, when the valve 13 opens, it, through the intermediacy of the rod 15 and the lever 14 carries the 70 valve 19 away from the tube 20 so that a portion of the water may flow unobstructed to the alarm system.

When the purpose of the water has been effected, the water supply is shut off, whereupon the valve 13 drops by gravity to its seat 6 and carries the valve 19, through the intermediacy of the rod 15 and the lever 14, to its seat against the tube 20, where it is held by pressure of the water in the chamber 3 and shuts off the alarm. If the system is to continue in use as a dry-pipe system the water is drained off through the pipes 26 and 28, and the valve 11 is closed, but if it is to be used as a wet pipe system the valve 11 is left open and water is admitted to the system until a sufficient quantity has accumulated above the valve 13 to hold the same closed until another sprinkler head opens.

From the foregoing it will be understood 90 that when a sprinkler head opens my valve becomes automatically converted from a dry pipe to a wet pipe valve and continues as a wet pipe valve without attention or adjustment of any kind after the sprinkler head is closed and water is again turned into the system. My valve also is automatically converted from a dry pipe to a wet pipe valve if the air under pressure in chamber 4 condenses or becomes sufficiently 100 reduced from other causes to allow the valve to trip. When this occurs the water flows through the valve and to the alarm until the pressure in the system equalizes, whereupon the valve 13 closes by gravity and allows valve 19 to be seated by pressure of the water in chamber 3, and shut off the alarm.

Owing to the ease with which the valve 13 can open the valve 19, due to the leverage obtained through the rod 15 and the lever 14, said valve 19 and its seat may be made considerably larger than usual and thus insure a sufficient supply of water to the alarm to properly operate the same. The leverage referred to also is sufficient to readily unseat the valve 19, should it corrode and tend to stick to its seat. To compensate for the space occupied by the lever 14 and the rod 15 when the valve 13 is open, the port through the valve seat 6 is made slightly 120 larger than the port through the seat 5, so that the flow of water through the seat 6 will be unobstructed.

In the modified form disclosed by Fig. 4, the parts are the same as in Fig. 1, except 125 that the lower end of the valve case 1^a extends at an angle of forty-five degrees to its upper end instead of at an angle of ninety degrees as in Fig. 1. The type of case disclosed by Fig. 1 is employed in mak-

ing connections to horizontal supply pipes, while the type disclosed by Fig. 4, is used in making connections to vertical supply pipes.

While two forms of the device have been disclosed, it is obvious that various other modifications in the construction, combination, and arrangement of parts can be made without departing from the spirit or scope of the claims.

10 Having thus described my invention, what I claim and desire to secure by Letters Patent, is:

1. In a pipe valve of the character described, a casing, a valve seat therein, a valve adapted to bear against said seat, an alarm tube extending into said casing, a valve to close said alarm tube, a lever pivoted to the interior of the casing and having the last-mentioned valve pivoted there-
20 to, and a rod pivotally connected to the first valve and the lever and adapted to unseat the alarm valve when said first valve opens.

2. In a pipe valve of the character described, a casing, two valve seats therein, two valves adapted to bear respectively against said seats, a rod connected to one of said valves and adapted to transfer pressure at an angle therefrom against the other valve, an alarm tube communicating with said casing, a valve to close said alarm tube, and a lever carrying the last-mentioned valve and connected to the above-mentioned rod.

3. In a convertible device of the character described, a casing having two valve seats arranged therein at an angle to each other, upper and lower pivoted valves mounted independently of each other so that both may be closed or a certain one may be left open and a member extending at an angle from the upper valve and adapted to exert pressure on the lower valve when closed, in accordance to the angularity of said member.

4. In a convertible device of the character described, a casing having two valve seats arranged therein at an angle to each other, upper and lower pivoted valves mounted independently of each other so that both may be closed or a certain one may be left open and a rod pivoted to the upper valve to extend obliquely therefrom and exert pressure on the lower valve when closed, in accordance to the obliquity of said rod.

5. In a device of the character described, a casing, upper and lower valves pivoted to said casing, a lever pivoted to the casing and adapted to bear against the lower valve when closed, an alarm valve carried by said lever, an alarm tube against which said alarm valve is adapted to seat, and a member operably-connected to the upper valve

and said lever to hold the latter firmly against the lower valve when closed and unseat the alarm valve when the upper valve opens.

6. In a pipe valve of the character described, a casing, a valve seat therein, a valve pivoted to the interior of the casing and adapted to bear against said seat, an alarm valve arranged beneath the first valve, a lever pivoted to the interior of the casing and mounting intermediate its ends said alarm valve, and a rod operably-connected to the free end of said lever and the first valve whereby the alarm valve is unseated when the first valve opens.

7. In a pipe valve of the character described, a casing, a valve pivoted in the upper portion of said casing, an alarm valve arranged beneath the first-mentioned valve, a lever pivoted to the inner side of the casing and upon which the alarm valve is mounted, and a member pivoted at its ends to the first-mentioned valve and the lever to coact with the latter in unseating the alarm valve.

8. In a pipe valve of the character described, a casing, a valve pivoted in the upper portion of said casing and adapted to be held in closed position by air pressure thereon, a rod connected to said valve, a member pivoted at one end to said casing and at its opposite end to the free end of said rod, a valve pivoted in the lower portion of the casing and against which said member bears, and a movable seat held by water pressure against the lower valve, a portion of said pressure being transmitted to the valve pivot, the remainder being exerted against the free end of the member and transmitted through the rod to the upper valve where a part of the pressure is exerted on the pivot in a plane parallel to said upper valve, the remainder of the pressure tending to lift said upper valve against the air pressure on the top thereof.

9. In a pipe valve of the character described, a casing, two valve seats therein, two valves adapted to bear respectively against said seats, and a rod connected to one of said valves and extending at an angle therefrom to the free side of the other valve, and adapted to transfer pressure from the lower valve to the upper valve obliquely thereto, a part of said pressure being exerted on the pivot of the upper valve parallel to said valve.

In testimony whereof I affix my signature, in the presence of two witnesses.

WILLIAM N. BALLARD.
